3 SHEETS—SHEET 3.

UNITED STATES PATENT OFFICE.

ANTON WELLERT, OF BINGHAMTON, NEW YORK.

MAGNET FIRE-ALARM SYSTEM.

1,424,963.

Specification of Letters Patent. Patented Aug. 8, 1922.

Application filed February 14, 1922. Serial No. 536,494.

To all whom it may concern:

Be it known that I, ANTON WELLERT, a citizen of the United States, residing at Binghamton, in the county of Broome and State of New York, have invented certain new and useful Improvements in Magnet Fire-Alarm Systems, of which the following is a specification.

My invention relates to improvements in magnet fire alarm systems and signal systems, and it has for its object to provide a signal mechanism, simple in construction and effective in operation, and controlled and actuated by the action of heat, aided by gravity and which in practical operation will produce signals in conjunction with or without a telephone, warning of fire.

With these objects in view my invention consists of certain novel features of construction and arrangement of parts, as will be hereinafter more particularly described and pointed out in the claims, reference being had to the accompanying drawings, in which—

Fig. 1 is a side view of a part of my device.
Fig. 2 is a front view of the housing or casing of my device.

Fig. 3 is a side view of a part of my device.
Fig. 4 is a side view of a part of my device.
Fig. 5 is a side elevation of part of my device.

Fig. 6 is a front view of my device in casing, in operative relation with the telephone.

The same reference characters denote like parts in each of the several figures of the drawings.

In carrying out my invention and in the construction of my device I provide a casing or housing A which has mounted upon it a hinged lid B, by means of the hinges 2, 2; within the casing A, I have pivotally mounted an elongated support, on which is mounted a thermometer body C, the support being mounted on pivot 3; the body C has in its outer end the usual mercury container 4, with tube 4'; the thermometer body so pivotally supported is adapted to be tipped into the position shown in the dotted outline C', and to aid in this pivotal movement, at the opposite end of body C and mounted on the support I have the vertically projected weight 4'', and for a graduated adjustment in the pivotal movement of the body C and balancing of the same, I have mounted in the outer end of the support the turn screw 5. Mounted on the inner side

wall of the housing A, I have a guide way 6 having the guides 7, 7 with inwardly bent edges. On the guide way 6 I slidably mount a base plate 9 having two opposite rectangular sides, and on which base plate 9, I mount the tripping and actuating mechanism D. Mounted also on the inner side wall of housing A, I have the magnet D' as shown in Fig. 1. Over an opening in the lid B and mounted in any convenient manner, I have the signal bell 8; the actuating spring gearing and tripping mechanism D of my device is shown in Figs. 4 and 5, as mounted on the plate 9; the plate 9 has the 2 parallel sides 10, 10. Mounted between the sides 10, 10 I have a series of shafts; a winding shaft 11, on which is mounted the gear 12 and ratchet gear 12' and winding spring 13; also the shaft 14, on which is mounted 75 gears 15 and 16, the gear 16 meshing with gear 12; also the shaft 17 on which is mounted the gears 18 and 18', the gear 18' meshing with gear 15; also the shaft 17' and on shaft 17' I have mounted the ratchet 19' contacting with gear 18, and also mounted the bell hammer 19 positioned to contact with the bell 8 when the lid B is closed; also I have the shaft 20 and mounted thereon I have the projecting tongue 21 positioned to 85 removably contact with hammer 19; on the outer end of shaft 20 I have the turn handle 22, and on the end of shaft 11, I have the winding handle 23; on the side 10' I have mounted a vertical support, from the ends 90 of which project the lugs 24, 24 forming a pivot support for the pivot 25 and on 25 I have pivotally mounted the spring bar 26 having the outer vertical end projections 27, 27. On the end of plate 9 I have a pivot support 28 and in which is the pivot 29, and on pivot 29 I have pivotally mounted the collar 31' and on which I have mounted the telephone switch arm 30 adapted to vibrate on the pivotal support 31'. The arm 30 is 100 formed of the body portion a and mounted thereon a curved spring bar or trigger support b; the body a has at its inner end the projection 32 and the spring bar b has at its inner end the angular projection 32' adapted to contact with the vertical pin 32'' mounted in plate 9; mounted on shaft 11 I have a beveled faced trip 33, the sloping face of which is in alinement with the ends of projections 32 and 32' and adapted to slidably contact 110 therewith. On the opposite end of shaft 20, I have the lug 34, adapted when in adjust-

ment to extend over and contact with the pivoted spring bar 26. It is to be noted that the pivoted support for body C is in alignment with the spring bar 26 and the vertical end projection 27; and when the mercury influenced by heat temperature moves along the thermometer tube 4' the outer end of the pivoted support and the body C tips downward influenced by gravity and drawn 5 by the magnet D', until in its downward movement the end of the support for the body C strikes the projection 27 on spring bar 26 which turns bar 26 on pivot 25 and moves the opposite end of the bar 26 from 10 contact with lug 34, releasing lug 34 and shaft 20 and with it tongue 21 from contact with hammer 19, releasing hammer 19, and thus permitting the spring actuated gearing connected with shaft 20 to revolve, and with 15 the resultant movement of hammer 19 actuated by the ratchet 19' and contacting with the bell 8, and the bell is rung sounding an alarm. In operative position my device is 20 preferably mounted against a wall or other vertical surface. As a further feature in the 25 operative movement of my device, as connected with a telephone, I have the telephone body E, with the usual projecting receiver arm 35. The projecting switch arm 30 of 30 my device may have its outer end in any convenient form to contact with and raise receiver arm 35, and in its spring actuated movement, produce in its contact a vibratory and operative movement of the telephone receiver arm 35 producing sufficient movement 35 of the receiver arm to sound a telephone alarm, by the ringing of the telephone bell. In the operation of my device, in further detail, having wound up spring 13 of the ringing mechanism D, by turning handle 23 on the winding stem or shaft 11, I adjust the pivoted spring bar 26 by turning handle 22, which turns shaft 20 which moves tongue 21 into a position against the clapper arm 19 40 and turns lug 34 into a lateral position over pivoted spring bar 26, holding it taut, in a rigid position; a fire occurs, the heat acting upon the mercury causes it to pass along tube 4' and causing by this changed position 45 50 the pivoted thermometer support and body C to tip downward, the downward movement intensified by the magnet D' causing the body C to forcibly contact with the vertical projection 27 on pivoted spring bar 26, causing it to turn on pivot 25, and thereby become released from engagement with the lug 34, and thereby releasing shaft 20 and tongue 21 from contact with bell hammer 19, thereby releasing the spring mechanism 55 60 gearing and causing hammer 19 to strike bell 8 ringing the same until spring 13 is unwound; in this movement shaft 11 re-

volves and with it trip 33 which alternately contacts with projection 32 on arm 30 and projection 31 on spring support b, thereby 65 releasing spring support b, causing an upward movement of arm a and thereby moving upward the telephone receiver arm 35 with which arm a is in contact, as shown in Fig. 6, causing the telephone bell to ring as 70 before described. And thus it is possible with this device to produce automatically a double alarm. The spring mechanism is mounted on plate 9 which is removably positioned between guides 7, 7 in casing A. 75 It is to be noted that the relative position of the turn screw 5 as shown in Fig. 3 may be adjusted according to a scale indicated on the support, so as to adjust the limit of balance to correspond with the degree scale 80 of the thermometer body C.

Having thus described my invention what I claim as new and for which I desire Letters Patent is as follows:

1. In combination an alarm mechanism, a driving mechanism therefor a primary trip lever for stopping the driving mechanism, a primary atmospherically and magnetically controlled mechanism for operating the trip lever to release the driving mechanism. 85
2. In combination with an alarm mechanism, a driving mechanism therefor, a trip lever holding the driving mechanism in inoperative control, a primary adjustable and atmospherically and magnetically controlled mechanism for releasing the trip lever, for releasing the driving mechanism. 90
3. In combination, an alarm mechanism, a driving mechanism therefor an atmospherically controlled and magnetically controlled trip lever means for adjusting the operation of said lever, an intermediate trip lever for holding the driving mechanism in inoperative position, operative means for operating the trip lever to release the driving mechanism when the mechanism becomes heated to a predetermined degree, comprising a pivoted thermometer body, a magnet, and operative connection between thermometer body and the trip lever substantially as described. 100
4. In an alarm mechanism, a signal element, driving mechanism for actuating the signal element, a spring lever for holding the driving mechanism in inoperative position, a pivoted thermometer body adapted to engage the spring lever to release the driving mechanism upon a rising temperature to a predetermined degree and a magnet for assisting in the operation of the pivoted thermometer body. 115

In testimony whereof, I have affixed my signature.

ANTON WELLERT.
